Primary Examiner — T. Chase Nelson*Assistant Examiner* — Mark Cavanna(74) *Attorney, Agent, or Firm* — Harness, Dickey & Pierce**(57) CLAIM**

I claim, the ornamental design for a patient table, as shown and described.

DESCRIPTION

FIG. 1 is the front perspective view of a patient table showing my new design;

FIG. 2 is a front elevation view thereof;

FIG. 3 is a rear elevation view thereof;

FIG. 4 is a side elevation view thereof;

FIG. 5 is another side elevation view thereof;

FIG. 6 is a top plan view thereof; and,

FIG. 7 is a bottom plan view thereof.

The broken lines are included for the purpose of illustrating unclaimed portions of the patient table and form no part of the claimed design.
